UNITED STATES PATENT OFFICE

2,506,179

FLUID RESISTOR

John F. Taplin, West Newton, Mass.

Application May 15, 1946, Serial No. 670,008

14 Claims. (Cl. 138—43)

1

This invention relates to fluid resistors, and has as an object, the provision of a fluid resistor, the resistance of which can readily be varied over a wide range.

Many automatic control instruments utilize fluids such as air and liquids as motion transmitting mediums, and require resistances in the fluid circuits as for adapting instruments to particular conditions of use. Capillary tubes have been preferred as resistive elements since their effect is readily calculable, and they attenuate pressures causing fluid flow without the difficulties of maintenance small orifices would be expected to require, but since in the past it has been possible to adjust them only by changing their dimensions, it has been necessary where quick and precise adjustment has been required, to use special forms of needle valves, or porous plugs the resistance of which was varied by compression elements.

This invention provides a fluid resistor, the resistance to fluid flow of which is readily and continuously adjustable. Two fluid flow passages are provided, one passage having a relatively high resistance, and the other having a relatively low resistance, the passages being interconnected at closely spaced points along their lengths. The low resistance path can be closed off at any point along its length by the movement of a plunger therethrough. Where the plunger has not closed off the low resistance passage, the fluid flow is through both passages, and the resistance to fluid flow is relatively slight. Where the plunger has closed off the low resistance passage, the fluid flow is through the high resistance passage, and the resistance to fluid flow is relatively great. Thus by movement of the plunger, the resistance of the resistor can be varied continuously in minute steps from maximum to minimum and vice versa.

The invention will now be described with reference to the drawing, of which:

Fig. 1 is a side elevation, with internal components indicated by dashed lines, of a fluid resistor embodying this invention;

Fig. 2 is a sectional view along the lines 2—2 of Fig. 1;

Fig. 3 is a diagrammatic view illustrating the construction of the discs used in the resistor of Fig. 1, and illustrates by the lines with arrows, the fluid flow through the resistor with the relatively large fluid flow passage completely closed by the movable plunger;

Fig. 4 is a view similar to Fig. 3 but illustrates the fluid flow through the resistor with the relatively large passage wide open;

2

Fig. 5 is a view similar to Fig. 3 except that orifices are used for providing the increased resistance in the flow passage having highest resistance;

5 Fig. 6 is a diagrammatic view illustrating the construction and arrangement of the discs providing fluid passages, in another embodiment of the invention;

Fig. 7 is a diagrammatic view illustrating the 10 construction and arrangement of the discs providing fluid passages, in still another embodiment of the invention;

Fig. 8 is a side elevation, partially in section, 15 of a fluid potentiometer embodying this invention;

Fig. 9 is an end elevation of the central disc in the potentiometer of Fig. 8, and

Fig. 10 is a diagrammatic view, in reduced 20 scale, of the connection of the fluid potentiometer of Fig. 8 in a fluid circuit.

Referring first to Figs. 1 to 4 inclusive, the fluid resistor 10 consists of a cylindrical casing having threaded ends with the end caps 11 and 12 screwed thereon. Stacked in the casing between 25 the end caps are the alternately arranged transfer discs 13 and resistance discs 14. Figs. 3 and 4 illustrate the order of arrangement of the discs.

The transfer discs 13 are similar and have the 30 relatively large, circular openings 16 for the reception of the resistance adjusting plunger 15, and have the relatively small openings 17 in the capillary passage as will be described. Alternate transfer discs 13 are rotated 180 degrees about their axes as illustrated by Figs. 3 and 4, so that 35 alternate openings 17 are diametrically opposite. The uppermost disc of Fig. 3 and of Fig. 4 is the disc 13 of Fig. 2, the disc through the opening 17 of which, the fluid leaves the resistor.

The inlet tube 18 extends through an opening 40 in the end cap 12 and connects with the inlet opening 17 in the inlet disc 13. The outlet tube 19 extends through an opening in the end cap 11 and connects with the opening 17 in the outlet disc 13.

45 The resistance discs 14 are similar and are similarly placed in the resistor. They have the relatively large, circular openings 20 having the same diameter as the openings 16 in the discs 13, and are aligned with the openings 16 for the reception of the plunger 15. The discs 14 also have the diametrically opposite, circular openings 21 and 22 which are interconnected by the slits 23. The slits 23 are connected by the slits 24 with the openings 20.

When the plunger 15 is fully withdrawn from the openings 20 in all the resistance discs 14,

the fluid through the resistor has two passages, one the passage of relatively low resistance straight through the aligned, relatively large openings 16 in the discs 13, and 20 in the discs 14, and the other the capillary passage of relatively high resistance through the openings 17 and the slits 23.

When the plunger 15 is inserted through all of the openings 20 in the discs 14, then the low resistance passage is closed off as illustrated by Fig. 3. The flow through the capillary passage is indicated by the lines with arrows, the flow being shown to be from the opening 17 in the lowermost disc 13, through the opening 22, the slit 23 and the opening 21 of the adjacent resistance disc 14, into the opening 17 of the next adjacent disc 13, then through the opening 21, the slit 23 and the opening 22 of the next adjacent disc 14, and then out the opening 17 in the uppermost disc 13.

Fig. 4 illustrates the plunger 15 completely withdrawn from the discs so that the relatively large, low resistance passage through the resistor is completely open. The high resistance passage is the same as that described in the foregoing in connection with Fig. 3. The low resistance passage is seen to be from the slit 23 in the lowermost resistance disc 14 into the opening 20 in the same disc, and then through the openings 16 and 20 in the discs between same and the outlet.

As the plunger 15 is inserted to close off the openings 16 and 20 in some of the discs, then the low resistance passage through those discs is closed leaving the only passage through those discs to be the capillary passage.

While Figs. 3 and 4 illustrate five discs as forming the two flow passages, any multiple of four may be used depending upon the total resistance required.

The plunger 15 can be adjusted to engage more or fewer discs for providing more or less resistance. Thus the resistive elements can be added or subtracted one at a time for providing minute resistance changes, or can be added or subtracted in as many numbers at a time as are required for providing any desired resistance change within the capacity of the resistor.

Fig. 5 is similar to Fig. 3 except that the resistance discs 14 instead of containing the openings 21 and 22 interconnected by the slits 23, have instead, slots 30 with the orifices 31 therein on the opposite sides of the slits 24, and except that the transfer discs 13 instead of having the relatively small openings 17 therein, have instead the larger openings 32.

The pressure drops are across the orifices rather than along the length of a capillary as in the case of Figs. 3 and 4. Otherwise the fluid flow and the resistance adjustment are the same as described in the foregoing in connection with Figs. 3 and 4.

Fig. 6 illustrates an embodiment of the invention in which square end, resistance and transfer discs are used. The uppermost disc 40 is an end disc of which there are two, only one of which is illustrated since the two are duplicates. The discs 42, 43, 44 and 45 are the resistance discs, and the discs 46, 47, 48 and 49 are transfer discs, the resistance and transfer discs being alternately arranged as in Figs. 1-5. The discs all have the similar, aligned, circular openings 41 for the reception of a resistance varying plunger corresponding to the previously described plunger 15.

The resistance discs 42, 43, 44 and 45 have the similar, relatively long slits 50, 51, 52, 54, 55 and

56 formed therein, and have the relatively short slits 53 connecting with the openings 41 therein.

The transfer discs 46, 47, 49 and 49 have the bridging slits 57, 58, 59, 60 and 61 which interconnect the ends of the slits in the resistance discs for connecting same in series with each other, and have the relatively small openings 39 for interconnecting the slits in adjacent resistance discs.

The lengths of the slits 50-56 inclusive, are substantially greater than the distances between the outer edges of the slits 50 and 56. The slits 57, 58 and 59 are further from the centers of the discs than are the slits 50 and 56, and are covered by the unperforated metal between the outer edges of the slits 50 and 56 and the adjacent outer edges of the discs in which they are formed, whereby neither of the slits 50 or 56 in one disc can bridge the slits 50-56 in another disc.

20 The end discs 40 have the relatively small, circular openings 71 therein, serving in the disc 40 illustrated, as a fluid inlet opening, and serving in the other disc 40 (not shown) as a fluid outlet opening.

25 Facing Fig. 6 of the drawing, the resistance disc 43 is rotated in a counterclockwise direction through an angle of 90 degrees with respect to the resistance disc 42; the resistance disc 44 is similarly rotated with respect to the disc 43, and 30 the disc 45 is similarly rotated with respect to the disc 44. The transfer disc 47 is similarly rotated with respect to the transfer disc 46; the transfer disc 48 is similarly rotated with respect to the transfer disc 47, and the transfer disc 49 is similarly rotated with respect to the disc 48.

35 The slits in the resistance and transfer discs of Fig. 6 form a capillary passage. The fluid enters the passage through the opening 71 in the disc 40, then passes into the lower end of the slit 50 in the disc 42, then passes out the upper end of the slit 50 into the left hand end of the slit 57 in the disc 46, then out the right hand end of the slit 57 into the upper end of the slit 51 in the disc 42, then out the lower end of the slit 51 into the left hand end of the slit 60 in the disc 46, then out the right hand end of the slit 60 into the lower end of the slit 52 in the disc 42, then out the upper end of the slit 52 into the left hand end of the slit 58 in the disc 46, then out the right hand end of the slit 58 into the upper end of the slit 56 in the disc 42, then out the lower end of the slit 56 into the opening 39 in the disc 46, then through the opening 39 into the right hand end of the slit 50 in the disc 43, then out the left hand end of the slit 50 into the lower end of the slit 57 in the disc 47, then out the upper end of the slit 57 into the left hand end of the slit 51 in the disc 43, then out the right hand end of the slit 51 into the lower end of the slit 60 in the disc 47, then out the upper end of the slit 60 into the right hand end of the slit 52 in the disc 43, then out the left hand end of the slit 52 into the lower end of the slit 58 in the disc 47, then out the upper end of the slit 58 into the left hand end of the slit 54 in the disc 43, then out the right hand end of the slit 54 into the lower end of the slit 61 in the disc 47, then out the upper end of the slit 61 into the right hand end of the slit 55

in the disc 43, then out the left hand end of the slit 55 into the lower end of the slit 59 in the disc 47, then out the upper end of the slit 59 into the left hand end of the slit 56 in the disc 43, then out the right hand end of the slit 56 into the opening 39 in the disc 47, and through the opening 39 into the upper end of the slot 50 in the disc 44.

The flow through the discs 44 and 48 is the same as that described in the foregoing in connection with discs 42 and 46, and the flow through the discs 45 and 49 is the same as that described in the foregoing in connection with discs 43 and 47. The opening 39 in the disc 49 is aligned with the lower end of the slit 50 of another disc corresponding to the disc 42, in the same way as the opening 71 in the end plate 40 is aligned with the slit 50 in the disc 42, and the cycle is repeated through other sets of eight discs similar to the discs 42, 46, 43, 47, 44, 48, 45 and 49, and similarly arranged.

The opening 39 in the last or fluid outlet, transfer disc corresponding to the disc 49 of Fig. 6, would be aligned with the opening 71 in the outlet end disc of the resistor, similar to the disc 40 of Fig. 6 but placed at the opposite end of the stack of discs.

The low resistance fluid passage would be through the openings 41 in the discs of Fig. 6, and a resistance adjusting plunger similar to the plunger 15 of Figs. 1-5 would be movable through the openings 41 for varying the resistance of the resistor. The slits 53 connect the openings 41 with the centers of the capillary passages through the resistance discs. When the resistance adjusting plunger is removed from an opening 41 in a resistance disc, then the capillary passage through that disc is shunted by the low resistance passage through the opening 41, thereby greatly reducing the resistance of that disc. When the resistance adjusting plunger is inserted in an opening 41 in a resistance disc, then the low resistance passage through that disc is closed whereby all the fluid flow is through the high resistance, capillary passage.

The small circular openings 70 in the four corners of the discs of Fig. 6 are for receiving small rods or bolts for holding the discs aligned in a stack that can be inserted in a casing.

Fig. 7 illustrates another embodiment of the invention in which transfer discs are not used. The resistance discs are arranged in sets of threes consisting of discs 72, 73 and 74. The discs are similar and have the slits 75 formed as circular arcs, each arc extending through 120 degrees, and having the circular openings 76 and 77 formed in its ends. The disc 73 is rotated through an angle of 120 degrees with respect to the disc 72, and the disc 74 is rotated through an angle of 120 degrees with respect to the disc 73 as illustrated by Fig. 7. The end discs 82 of which there are two, only one of which is illustrated, each has a small circular opening 83 formed therein and so located that it can be aligned with one of the openings 76 and 77. The discs have the relatively large, circular openings 80 through the centers thereof, for the reception of a resistance adjusting plunger similar to the plunger 15 described in the foregoing in connection with Figs. 1-5. The discs 72, 73 and 74 have the slits 84 connecting the centers of the slits 75 with the central openings 80.

A capillary fluid passage is provided through the opening 83 in the inlet end disc 82, then through the opening 77 in the disc 72 aligned

therewith, then through the slit 75 in the disc 72, then through the opening 76 in the disc 72 into the aligned opening 77 in the disc 73, then through the slit 75 in the disc 73, then through the opening 76 in the disc 73 into the opening 77 in the disc 74, then through the slit 75 in the disc 74 and through the opening 76 in the disc 74 into an opening 77 in another disc (not shown) corresponding to the disc 72 and forming the inlet resistance disc in another set of discs, the number of sets of discs depending upon the total resistance required. An end plate similar to the end plate 82 of Fig. 7 would have its opening 83 aligned with the opening 76 in the last or outlet resistance disc corresponding to the disc 74.

The openings 80 provide a fluid passage of relatively low resistance which can be variably closed off by a plunger through the openings 80 in the same way as the plunger 15 closes off the low resistance passages described in the foregoing in connection with Figs. 1-5.

The resistance discs in each embodiment of the invention are seen to be duplicates, as are the transfer plates. They can be manufactured using standard stamping machinery, the corresponding openings and slits being formed by the same tools so that they will be in proper alignment when assembled into resistors. The openings for the resistor varying plungers in the discs of each embodiment of the invention can be punched with the same tool thus providing identical sizes so that the plunger can be moved through the discs with small friction drag and therefore small effort.

The transfer discs illustrated may have the same thickness for providing a linear relation between plunger movement and resistance, or they may be made to have varying thicknesses so that a logarithmic relation between plunger movement and resistance may be provided.

Figs. 8, 9 and 10 illustrate how a fluid resistor embodying features of this invention can be arranged as a potentiometer. The potentiometer illustrated has resistance discs and transfer discs similar to those of Figs. 1-4, except that a center tap plate 90 replaces the center resistance disc. The plate 90 has a radial extension 91 with a slit 92 therein which connects with the slit 93 aligned with the slits 23 in the resistance discs. The inlet tube 94 of the cylindrical casing 95 is aligned with and connects with, the inlet opening in the inlet disc corresponding to the inlet opening 17 in the inlet disc 13 of Figs. 3 and 4. The outlet tube 96 is aligned with and connects with the outlet opening in the outlet disc 13 corresponding to the opening 17 in the outlet disc 13 of Figs. 1-4.

The plunger 97 extends through the relatively large opening 98 in the plate 90 which is aligned with the openings in the resistance and transfer discs corresponding to the openings 20 and 16 shown by Figs. 3 and 4. The plunger 97 has an axial opening 99 therein which connects with the opening 100 in the upper periphery of the plunger, the remainder of the plunger being solid. The opening 100 has a width equal to that of two of the discs of Figs. 3 and 4, and as the plunger is moved as described in connection with Figs. 3 and 4, through the resistor for varying its resistance, the opening 100 overlaps pairs of the discs in the resistor.

The plunger 97 has a length sufficient to extend through the resistor when the opening 100 therein is moved from one extreme end of the casing 95 to the other end thereof, whereby it can serve as the plunger 15 described in connection with Figs.

3 and 4 serves to adjust the resistance of the resistor.

The extension 91 of the plate 90 extends into a tube connection 102 at the top of the casing 95 and which is adapted to be connected, as illustrated by Fig. 10, by the tube 103 to one end of the pressure manometer 104, the other end of which is connected to the axial opening 99 in the plunger 97.

In operation, if a pressure differential is maintained across the resistor by maintaining a flow of fluid therethrough between the inlet tube 94 and the outlet tube 96, the manometer 104 will indicate the pressure difference between the center tap slit 92 in the plate 90, and the pick-up opening 100 in the plunger 97. As with any center tapped potentiometer, a zero indication will be obtained on the manometer when the opening 100 is in alignment with the slit 92 in the center plate 90.

While embodiments of the invention have been described for the purpose of illustration, it should be understood that the invention is not limited to the exact apparatus and arrangements of apparatus illustrated, since modifications thereof may be suggested by those skilled in the art, without departure from the essence of the invention.

What is claimed is:

1. A fluid resistor comprising a plurality of stacked discs, means forming a tortuous fluid passage through said discs, means forming a non-tortuous fluid passage through said discs, means inter-connecting said passages at a plurality of closely spaced points along their lengths, and a resistance adjusting member movable through said non-tortuous passage.

2. A fluid resistor according to claim 1 in which the tortuous passage is a capillary.

3. A fluid resistor according to claim 1 in which the tortuous passage includes a plurality of orifices.

4. A fluid resistor comprising a plurality of stacked discs, alternate of said discs having tortuous fluid passages formed therein, the discs between said alternate discs having passages therethrough interconnecting the passages in the alternate discs, said discs having a non-tortuous fluid passage therethrough, said alternate discs having fluid passages interconnecting said tortuous and non-tortuous passages, and a resistance adjusting member movable through said non-tortuous passage.

5. A fluid resistor according to claim 4 in which the tortuous passages are capillaries.

6. A fluid resistor according to claim 4 in which the tortuous passages include a plurality of orifices.

7. A fluid resistor comprising a plurality of stacked discs, alternate discs having a plurality of fluid passages therein, the discs between the alternate discs having fluid passages therein for connecting said first mentioned fluid passages in series, said discs having a common fluid passage therethrough, said alternate discs having fluid passages connecting said first mentioned passages with said common passage, and a resistance adjusting member movable through said common passage.

8. A fluid resistor according to claim 7 in which the first mentioned fluid passages are capillaries, and the common passage has a relatively large cross-sectional area.

9. A fluid resistor comprising a plurality of stacked discs, alternate discs having relatively

high resistance fluid passages therein, the discs between said alternate discs having passages therein connecting said passages in series, said discs having a common fluid passage of relatively low fluid resistance extending therethrough, said alternate discs having fluid passages connecting said relatively high resistance fluid passages with said common passage, and a resistance adjusting member movable through said common passage.

10. A fluid resistor comprising a plurality of discs having fluid passages of relatively high resistance connected in series, means forming a common fluid passage of relatively low resistance through said discs, means in said discs connecting the high resistance fluid passages therein with said common passage, and resistance adjusting means movable through said common passage.

11. A fluid resistor comprising means forming a plurality of fluid passages of relatively high resistance connected in series, a channel in said resistor connected at a plurality of closely spaced points along its length with said passages, and a pressure tapping member movable through said channel.

12. A fluid resistor comprising means forming a plurality of fluid passages of relatively high resistance connected in series and extending therethrough, a channel of relatively low resistance to fluid flow extending through said resistor, means forming other passages connecting said first mentioned passages with said channel at a plurality of closely spaced passages along its length, and a resistance adjusting member movable through said channel, said member having a pressure tapping opening therein connecting with said other passages.

13. A fluid resistor comprising a plurality of stacked discs, means forming a tortuous fluid passage through said discs, means forming a non-tortuous fluid passage through said discs, means forming other passages connecting said tortuous passage and said non-tortuous passage at a plurality of closely spaced points, and a resistance adjusting member movable through said non-tortuous passage, said member having a pressure tapping opening therein connecting with said other passages.

14. A fluid potentiometer comprising a plurality of stacked discs, means forming a relatively tortuous fluid passage through said discs, means forming a relatively non-tortuous fluid passage through said discs, cross passages interconnecting said passages at a plurality of points, means forming a passage connecting the centers of said tortuous and non-tortuous passages and the exterior of the potentiometer, and a member movable through said non-tortuous passage and having a hollow portion with an opening through its wall alignable with said cross passages.
